A. J. DILLEY.
GREASE GUN.
APPLICATION FILED JULY 2, 1919.

1,384,941.

Patented July 19, 1921.

Argus J. Dilley, INVENTOR
BY D. L. Thompson, ATTORNEYS.

UNITED STATES PATENT OFFICE.

ARZENO J. DILLEY, OF MUIR, MICHIGAN.

GREASE-GUN.

1,384,941.

Specification of Letters Patent. Patented July 19, 1921.

Application filed July 2, 1919. Serial No. 308,190.

To all whom it may concern:

Be it known that I, ARZENO J. DILLEY, of Muir, in the county of Ionia, in the State of Michigan, have invented new and useful 5 Improvements in Grease-Guns, of which the following, taken in connection with the accompanying drawings, is a full, clear, and exact description.

This invention relates to certain improvements in grease guns involving the use of 10 a pump of the reciprocatory piston type, having an inlet and an outlet in one end for communication respectively with a source of supply and a delivery nozzle, and reference 15 is hereby made to my copending application, Serial No. 277,827, filed Feb. 18, 1919.

The grease adapted to be used for lubricating purposes, and particularly as applied 20 to the various bearings of motor vehicles, is either put up in cans, pails or receptacles of 25 convenient size for delivery to the user and one of the objects of my present invention is to provide a pump which may be easily and quickly attached to an outlet from the can or pail and used in connection therewith in lubricating bearings or other parts, thus 30 permitting the pump to be used as the refilling medium for transferring the grease directly from the can to the bearing and avoiding the inconvenience of separate means for filling the pump.

Another object is to enable the valve, which controls the inlet and outlet ports of the pump cylinder, to be operated simultaneously with movement of the piston of the 35 pump so that the communication between the inlet port and the cylinder is opened and that between the outlet port and the cylinder closed at the end of the compression 40 stroke, while the communication between the outlet port and the cylinder is opened and that between the inlet port and the cylinder is closed at the end of the suction stroke of the piston.

Other objects and advantages relate to the 45 construction, form and arrangement of the parts for operating the said valve which is of the sleeve type and of the various details of construction of the device as will more 50 fully appear from the following description taken in connection with the accompanying drawings in which:

Figure 1 is a vertical cross section illustrating my invention as applied to a suitable 55 pail, can, or the like.

Fig. 2 is a similar view shewing the piston of the pump at substantially its limit of upward movement and with the inlet port closed and the outlet port opened.

Fig. 3 is a detail sectional view of the 60 sleeve valve and its directly associated parts.

Fig. 4 is a horizontal section through the lower end of the device intersecting the inlet and outlet ports from the pump cylinder.

The illustration discloses an ordinary 65 grease containing can or pail —1— having a suitable opening or outlet —2— preferably in the side wall thereof. For association with such a pail I provide a casing —3— having an elbow shaped inlet nozzle —4— 70 adapted to terminate near the bottom of the pail, and preferably diametrically opposite the inlet nozzle —4— is an externally threaded nipple —5— of a diameter suitable to pass through the opening —2— for 75 engagement with an internally threaded elbow —6— adapted for connection to a delivery tube —7— which may be of a flexible type and may terminate in a nozzle —8—, normally closed by cap —9— through the 80 medium of a spring —10—.

By tightly threading the elbow —6— upon nipple —5— a grease tight joint is formed and packing may be used if desired. This elbow —6— may be provided with a foot 85 rest —11—, if desired, and the elbow and foot rest may be formed of a single casting and in like manner the casing —3—, the inlet elbow —4— and nipple —5— may be formed of a single casting. 90

The casing —3— is preferably formed with an interior chamber of substantially cylindrical form and adapted to receive the lower end of a pump cylinder —12— which tightly fits within the casing and is secured 95 thereto in any suitable manner as by a screw —13—. The pump cylinder has suitable inlet and outlet ports —14 and 15— alined respectively with the inlet elbow —4— and the nipple —5—.

Within the pump cylinder —12— is arranged a suitable piston —16— mounted upon a tubular plunger —17— provided with an operating handle —18—. The piston may be mounted upon the plunger by 105 means of a nut —19— and a cap nut —20—, the cap nut being provided with a small axial opening adapted to permit free axial movement of a lifting rod —21— having a knob —22— positioned within the plunger 110

and of a cross sectional area greater than the cross sectional area of the axial opening in the cap nut to prevent removal of the knob therefrom and limit the sliding movement of the knob in one direction.

The lower end of the lifting rod —21— is connected in any suitable way to a sleeve valve —23— movable within the cylinder —12— and having openings —24 and 25— adapted to be brought respectively into registration with openings —14 and 15—. However, the openings —24 and 25— are arranged at different points lengthwise of the sleeve so that when opening —24— is in registration with port —14— the port —15— is closed by the sleeve valve and conversely when opening —25— is in registration with port —15— the inlet port —14— is closed by the sleeve valve. As shown, the lifting rod —21— is secured to the sleeve by means of a diametrical cross bar —26— through which the end of the rod passes and to which it is suitably connected as by nuts illustrated.

25 The knob —22— is of a size to freely slide within the tubular piston rod or plunger —17— and is of a suitable length to effect the operation about to be described.

When the piston is near the end of its compression stroke, assuming that the sleeve valve —23— is in the position shown in Fig. 2, the lower end of the piston, in this instance the cap nut —20— will contact with the cross bar or associated parts of the sleeve —23— and force the sleeve valve downwardly into contact with the bottom of casing —3— thereby closing the outlet port —15— and opening the inlet port —14—, the sleeve —23— remaining in the position shown in Fig. 2 until such point of contact is reached by reason of the free sliding relation of the knob —22— and the tubular piston rod —17—.

The sleeve valve —23— remains in this position until substantially the end of the suction stroke and until knob —22— comes into contact with cap nut —20— at which time the sleeve moves axially within the cylinder —12— simultaneously with the movement of the piston —16— and is thereby drawn to the position shown in Fig. 2 to close the inlet port —14— and open the outlet port —15— preparatory to discharge of the grease through said outlet port upon the next compression stroke of the piston. The operation of the sleeve valve controlling both the inlet and the outlet ports is thus effected by the normal movement of the piston at the time and in the manner desired to effect the proper operation of the device.

In order to limit the movement of the sleeve valve —23— and prevent its rotary movement within the pump cylinder, the sleeve may be provided with an axial slot

—27— into which the end of the screw 65 —13— may extend whereby the openings in the sleeve are always retained in proper vertical relation with reference to the ports in the pump cylinder. The upper end of the pump cylinder may as shown be provided with an overflow opening —28— to permit the discharge of any grease that may pass the piston and get in a position at the rear thereof.

Although I have shown and described a specific construction of apparatus in detail as involving, perhaps, a preferred embodiment of my invention, it will be obvious that various changes, modifications and substitutions may be made as to the form, construction and arrangement of the parts without departing from the spirit of the invention as set forth in the appended claims.

What I claim is:—

1. In a grease gun a piston cylinder having an inlet and an outlet, a piston movable therein, a sleeve valve controlling said inlet and said outlet, said valve connected to the piston for movement axially therewith to alternately open and close said inlet and said outlet.

2. A grease gun comprising a piston chamber having an inlet and an outlet, a piston movable therein, a tubular plunger for actuating the piston, a sleeve valve for controlling said inlet and said outlet and a lifting rod connected to the sleeve valve and movable within the tubular plunger to move said sleeve valve axially of said chamber during predetermined movement of the piston.

3. A grease gun comprising a casing having an inlet and an outlet, a piston cylinder having its lower end fitted within said casing and having inlet and outlet ports registering respectively with the inlet and outlet of the casing, a piston movable in said cylinder, a tubular plunger for actuating the piston, a lifter rod slidable within the tubular plunger and a sleeve valve connected to the lifter rod and capable of movement within the cylinder to control said valves.

4. A grease gun comprising a casing having an inlet and an outlet, a piston cylinder having its lower end fitted within said casing and having inlet and outlet ports registering respectively with the inlet and outlet of the casing, a piston movable in said cylinder, a sleeve valve within the cylinder for controlling said ports, a tubular piston rod for actuating the piston and a lifting rod secured to the sleeve valve and having a sliding movement within the piston rod for moving said sleeve valve axially of the cylinder at a predetermined stage of piston operation.

5. In a grease gun a piston cylinder, a piston movable therein, a sleeve valve slid-

able axially within the cylinder, said sleeve valve provided with a longitudinal slot and a member engaged with the cylinder and extending into said slot.

5 6. In a grease gun a casing having a substantially cylindrical seat and an inlet and an outlet therefrom, a tubular nipple leading from said outlet and an elbow formed with

an integral foot rest having removable engagement with said nipple.

In witness whereof I have hereunto set my hand this 25th day of June, 1919.

ARZENO J. DILLEY.
